DESIGN FOR A CONFECTIONERY PRODUCT

Edwin L. Elwell, East Orange, N. J., assignor to
Eskimo Pie Corporation, a corporation of Delaware

Application July 3, 1948, Serial No. 147,386

Term of patent 14 years

(Cl. D82—2)

To all whom it may concern:

Be it known that I, Edwin L. Elwell, a citizen of the United States, residing in East Orange, county of Essex, and State of New Jersey, have invented a new, original, and ornamental Design for a Confectionery Product, of which the following is a specification, reference being had to the accompanying drawing, forming part thereof.

Figure 1 is a front elevational view of a confectionery product, showing my new design;

Figure 2 is a side elevational view;

Figure 3 is a top plan view;

Figure 4 is a bottom plan view.

I claim:

The ornamental design for a confectionery product, substantially as shown.

EDWIN L. ELWELL.
